[57] CLAIM

The ornamental design for a combined electric plug and receptacle therefor, as shown and described.

DESCRIPTION

FIG. 1 is a perspective view of a combined electric plug and receptacle therefor showing my new design; FIG. 2 is a perspective view of the electric plug; the receptacle being omitted for purposes of disclosure; FIG. 3 is a perspective view of the receptacle as seen from the front and top, the bottom of the receptacle being flat and unornamented. The plug is omitted for purposes of disclosure; and FIG. 4 is a bottom plan view of the plug, the receptacle being omitted for purposes of disclosure.

FIG. 1

FIG. 2

FIG. 3

FIG. 4
